UNITED STATES PATENT OFFICE.

HENRY L. SLAUSON, OF BUFFALO, NEW YORK, ASSIGNOR TO WESTINGHOUSE ELECTRIC & MANUFACTURING COMPANY, A CORPORATION OF PENNSYLVANIA.

SWITCH MECHANISM.

Application filed October 9, 1920. Serial No. 415,781.

To all whom it may concern:

Be it known that I, HENRY L. SLAUSON, a citizen of the United States, and a resident of Buffalo, in the county of Erie and State of New York, have invented a new and useful Improvement in Switch Mechanism, of which the following is a specification.

My invention relates to switch mechanism and particularly to enclosed switches, such as are employed in controlling lighting and power circuits.

An object of this invention is to provide a simple and effective cover for the switch and fuse mechanism which may be readily detached from the panel supporting the switch and fuse members, when the switch is in open position.

Another object is to provide a switch mechanism wherein the door closing the opening in the housing through which the fuse members are accessible, is retained in latched position so long as the switch is in its closed position, and wherein the cover cannot be opened until the switch member is moved to its extreme open position.

Another object is to provide a switch mechanism wherein the switch is operated by a handle projecting through a slot in the cover and wherein provision is made to shield the slot to prevent access to the switch when the cover is closed.

A further object is to provide a switch mechanism that is simple and durable and inexpensive to manufacture and wherein the switch may be positively locked in open position.

These and other objects that will be apparent throughout the further description of my invention are attained by means of the switch mechanism hereinafter described and illustrated in the accompanying drawings, wherein:

Figure 1 is a view in front elevation, of my improved switch mechanism.

Fig. 2 is a vertical section on the line II-II of Fig. 1.

Fig. 3 is a transverse section on the line III-III of Fig. 2.

Referring to the drawings, the apparatus includes an insulating base 4, upon which is mounted two pairs of stationary switch-jaw members 5 and 6 and two pairs of fuse-clip members 7. Two switch blade members

8 are pivoted to the jaw members 5 and are

adapted to be moved into engagement with the jaw member 6 for closing the circuit through the supply terminals 9, the switch-jaw member 6, the switch-blade member 8, the jaw member 5, the conductor 10, the fuse clip 7, the fuse member 11, the clip 7 and the load terminal 12.

A protecting cover or housing 13 encloses the switch member and the fuse members. The cover comprises an arcuate section disposed directly opposite the switch mechanism, the generating center of curvature of the cover being co-incident with the axis of rotation of the switch-blade member. The portion of the housing surrounding the fuse member is somewhat shallower than that enclosing the switch mechanism and is provided with an opening 14 that is closed by a door 15, which is hinged to the housing by means of a hinge-pin 16. This door is normally held closed by means of a tension spring 17 that is secured, at one end, to the housing as at 18, and, at the other end, to the door.

The door is provided with a sliding latch 80 bar 19 that normally engages the ledge 20 turned inwardly from the lower end of the housing and prevents opening movement of the door. The latch-bar 19 is yieldingly retained in latched position by means of an 86 interlocking rocking bar 21 that is pivoted at 22 to clips 23, that are secured to that portion 24 of the cover that lies between the arcuate face thereof and the upper end of the opening 14 in the cover.

One end of the rocking bar is provided with an arcuate portion 25 that projects through a slot 26 provided in the upper end of the latch-bar 19. The opposite end 36 of the rocking bar extends toward the arcuate wall of the cover and is normally held in the position shown, wherein the latch-bar 19 is retained in closed or latched position, by means of a helical compression spring 27 that is disposed between the end 100 of the rocking bar and the wall 24 of the housing.

The switch blades 8 are connected by means of an insulating bar 28 to which a flat arcuate operating bar 29 is attached. An operating handle 30, having a threaded shank 31, extends in the slot 32 provided in the cover and is screwed into the bar 29. The nut 33, that is non-rotatable secured to the shank 31, serves as a shoulder for limit-

- ing inward movement of the handle. The nut is of greater width than the slot 32 and, consequently, the handle may not be removed to permit free movement of the cover unless the switch member is moved to an open position wherein the nut 33 registers with the wide section 34 of the slot 32, through which the nut may be withdrawn.
- 10 The left edge (Fig. 1) of the bar 29 is provided with a shoulder 35 that engages the end 36 of the rocking bar 21 when the switch is moved to open position. The end 36 is depressed thereby and the arcuate section 25 raises the latch bar 19 and unlatches the door 15. When the switch is moved to closed position, the spring 17 again closes the door.
- When the switch is in open position, the free end of the operating bar 29 projects through a slot 29' and a perforation 37 therethrough registers with an opening 38 provided in the clip 39 that is secured to the housing wall 22. A padlock 40 may be inserted in the perforations and the switch thereby locked in open position.
- When the bar 29 is in this position, the shoulder 35 is held just out of engagement with the rocking bar and, consequently, the fuse-compartment door is retained in closed position. The housing 13 is secured to the panel or base 4 by means of bolts 41 and 42 that are secured to the panel 4 and project through perforate wings 43 and 44, respectively, that are secured to the side walls of the housing. Wing nuts 45 and 46 serve to clamp the housing to the base.
- It will be observed that the wing nut 46 is disposed within the housing and is accessible only through the opening 14 that is closed by the door 15. The wing nut cannot be removed so long as the door is closed and, therefore, the cover cannot be removed until the switch is moved to an open position wherein the door is unlatched and wherein the handle 30 may be removed.
- It will be apparent from the foregoing that a switch must occupy an open position before the housing can be detached from the base or before the door closing access to the fuse compartment can be opened.
- While I have described and illustrated but one embodiment of my invention, it will be apparent to those skilled in the art that various changes, modifications, substitutions, ad-
- ditions and omissions may be made in the apparatus described without departing from the spirit and scope of my invention, as set forth by the appended claims.
- I claim as my invention:
1. Switch mechanism comprising a base, a switch member mounted upon the base, a cover for the switch member mounted upon the said base and having an opening therein, a movable door for closing the opening adapted to be released by the switch when the latter is in open position, and means accessible only through the said opening for detachably securing the cover to the said base. 60
2. Switch mechanism comprising a base, a switch member mounted upon the base, a cover for the switch member having an opening therein, a handle detachably secured to the switch member and projecting through the said opening in the cover and adapted to prevent the removal of the cover from the said base when the handle is secured to the switch member, and means including the cover for preventing the removal of the handle from the switch member except when the switch member is in predetermined open position. 70
3. Switch mechanism comprising a housing, a switch member within the housing, a hinged door for the housing, a latch carried by the door and engaging the said housing, a yielding member pivoted to the housing and operatively connected to the latch regardless of the position of the door for normally holding the latch in closed position and adapted to be actuated by the switch member to release the latch when the switch member is moved a predetermined distance to open position. 80
4. Switch mechanism comprising a switch member, a housing for enclosing the switch member, an operating handle for the switch extending exteriorly from one side of the housing and having an extension adapted to project exteriorly of the housing through an opening in another side of the housing only when the switch is in open position, and means co-operating with the projecting end of the extension for retaining the switch in open position. 90
- In testimony whereof, I have hereunto subscribed my name this sixth day of October, 1920.

HENRY L. SLAUSON.
